UNITED STATES PATENT OFFICE

108,412

DESIGN FOR A WOVEN TEXTILE FABRIC

Joseph George Levy, New York, N. Y., assignor to Louis Newman, New York, N. Y.

Application December 23, 1937, Serial No. 73,814

Term of patent 3½ years

To all whom it may concern:

Be it known that I, Joseph George Levy, a citizen of the United States of America, residing in the city of New York, county of New York, and State of New York, have invented a new, original, and ornamental Design for Woven Textile Fabric, of which the following is a specification, reference being had to the accompanying drawing, forming part thereof,

The figure on the drawing is a plan view of a woven textile fabric showing my new design.

I claim:

The ornamental design for a woven textile fabric substantially as shown.

JOSEPH GEORGE LEVY.
